UNITED STATES PATENT OFFICE.

CHARLES R. HARRIS, OF WILLIAMSPORT, PENNSYLVANIA.

DESIGN FOR A STEAM-RADIATOR.

SPECIFICATION forming part of Design No. 26,159, dated October 6, 1896.

Application filed September 24, 1894. Serial No. 523,985. Term of patent 14 years.

To all whom it may concern:

Be it known that I, CHARLES R. HARRIS, residing at Williamsport, in the county of Lycoming and State of Pennsylvania, have invented and produced a new and original Design for Steam-Radiators, of which the following is a specification, reference being had to the accompanying drawing, forming a part thereof.

10 The accompanying drawing is a perspective view illustrating my radiator.

The leading feature of my design consists in the representation of a pile of logs disposed

horizontally one upon another and a set of andirons made in the semblance of dragons. 15

A A represent these andirons, having their front portions fashioned to represent dragons.

C C indicate the horizontally-piled logs.

Having thus described my design, I claim—

20 The design for a steam-radiator substantially as herein shown and described.

CHAS. R. HARRIS.
